Smut Machine.

No. 17,869.

Patented July 28, 1857

UNITED STATES PATENT OFFICE.

EVERARD M. CLARK, OF LANCASTER, PENNSYLVANIA.

SMUT-MACHINE.

Specification of Letters Patent No. 17,869, dated July 28, 1857.

To all whom it may concern:

Be it known that I, EVERARD M. CLARK, of the city of Lancaster, county of Lancaster, and State of Pennsylvania, have invented 5 an Improved Smut-Machine; and I do hereby declare that the following is a full and exact description thereof, reference being had to the accompanying drawings and to the letters of reference marked thereon.

10 The nature of my invention is a propeller formed of four or more curved and fluted cast iron wings, attached to a center shaft, operating on the inside of a cylinder, for scouring the grain and blowing off the smut, &c.

15 To enable others skilled in the art to make and use my invention, I will proceed to describe its construction and operation.

A is the square frame work; B the square wooden spout, into which the grain is poured 20 at aperture C on the one side. It has another aperture D near the top on the opposite side. This spout B is located at top of cylinder or concave E and is about two feet high. The grain passes through this spout 25 in a wide sheet down into the cylinder E and upon the fluted wings of the propeller F, and by the curvature of the wings F the grain is thrown against the sharp edges of the concave E which produce a reaction and 30 force the grain back again toward the center of the propeller F, at the same time it is undergoing the scouring process, and the revolution of the propeller F is creating such a perfect draft of air, as to force the foul air 35 with the cheat, chaff and other smut (lighter than the wheat) upward, and out of the aperture D of the spout B above, and as the grain is descending through the spout B, it is receiving the blast from the propeller F, 40 and is being cleaned of smut, &c., before entering the cylinder E.

The vertical propeller F is formed of four or more curved and fluted cast iron wings attached to the center vertical shaft G, and 45 located and operating inside of the concave or cylinder E the whole length of cylinder, each wing scooping inwardly at bottom, somewhat screw shaped, as shown in the drawings, operating as a propeller to create 50 and drive the blast upward, and at the same time the outside edges of the wings operate within the grooved concave E about a quar-

ter of an inch from the projecting edges of the grooves of concave E to scour the grain. At the same time the grain is being scoured, 55 a portion of the chaff, smut, &c., is also forced through the square cast iron spout H (cast to the outside of cylinder E) into the large square wooden spout I, and thrown off at the opening J, the fan K below is also 60 blowing off all the chaff, smut, &c., upward out of the square spout I at the opening J and the grain being discharged from the cylinder E through the lower spout L into and out of the square spout I. By the aperture 65 M (which may be covered with wire gauze or perforated tin as usual) in the center of the bottom of the cylinder E a draft of fresh air is received and increased by the velocity of the revolving propeller F and discharged 70 above through the upper spout B, which likewise assists in blowing off the cheat, smut, &c., before they reach the cylinder E.

N is the driving pulley attached to shaft 75 G; O, a sliding door to be raised or lowered to regulate the opening or aperture J.

By the operation of this machine, the fan K below, and the fluted propeller F (in the cylinder E) are made to drive off all the chaff, smut, &c., while the scouring process is going on, and the grain is falling in through the spout B, and being discharged in a thoroughly cleaned state below at the spout L at the same time, while all the chaff, smut, &c., are blown out of the apertures D and J 85 of the square spouts B and I at the one side of the machine.

I am aware of wings being attached to a vertical shaft operating in a grooved concave or cylinder for scouring purposes, but 90 this I do not claim.

What I claim as my invention and desire to secure by Letters Patent is—

The shape and construction of the fluted propeller F as herein described, for the purposes of scouring the grain, and at the same time driving a blast upward, so as to blow off the cheat, smut, &c., out of the spout B above, before the grain passes down on to the wings of the propeller F and concave E. 100

EVERARD M. CLARK.
